UNITED STATES PATENT OFFICE.

SAMUEL ARNOLD, 3d, OF BEN AVON, PENNSYLVANIA.

CONTROL MECHANISM FOR HOISTING APPARATUS.

1,425,569.

Specification of Letters Patent. Patented Aug. 15, 1922.

Application filed April 6, 1921. Serial No. 458,923.

To all whom it may concern:

Be it known that I, SAMUEL ARNOLD, 3d, a citizen of the United States, and resident of Ben Avon, in the county of Allegheny 5 and State of Pennsylvania, have invented certain new and useful Improvements in Control Mechanisms for Hoisting Apparatus, of which the following is a specification.

This invention relates to hoists and more particularly to mechanism for controlling the upward travel of the hoisting apparatus, and while not limited thereto, is particularly adapted to a motor driven high speed crane or bucket hoist, and has for its object 15 the provision of control mechanism adapted to be operated by the moving load to make and break the circuit to said motor by means of a limited switch.

Another object is to provide a mechanism 20 of this class that will permit over-travel of the load after the control apparatus has been tripped and the circuit broken to the driving mechanism.

A further object is to provide a control 25 apparatus of this type that will automatically reset the limit switch when the load is lowered.

A still further object is to provide a control mechanism that will not interfere with 30 the usual lifting cables and other moving parts of the hoists.

The above and other objects will be more fully brought out in the following specification and illustrated in the accompanying 35 drawings, in which:

Figure 1 is a side elevation of a hoist trolley having my invention applied thereto.

Figure 2 is a sectional end elevation of 40 the trolley on the line II—II of Figure 1.

Figure 3 is a somewhat diagrammatic 45 sectional side elevation of the limit switch for controlling the lifting mechanism of the hoist.

Figure 4 is a partial side elevation illustrating the manner in which the flexible operating cable is trained over the several pulleys at the left-hand end of Figure 1, several parts being omitted and broken away for clearness.

Figure 5 is a cross sectional view on the 50 line V—V of Figure 1.

Figure 6 is a typical wiring diagram for 55 hoisting apparatus of the class to which my invention belongs and shows my invention embodied therein.

Referring particularly to the drawings, the numeral 2 designates the hoist or crane trolley which carries the usual drums 3 and 4 operated by electric motors 5 and 6, respectively. The drums 3 and 4 carry the usual 60 hoisting and closing ropes 7^a and 7^b which are operatively connected to the bucket or other load device 7 in the usual manner.

The above apparatus will not be described 65 further in detail since it is not a part of this invention.

In carrying out my invention, I mount a rotary limit switch 10 on the trolley 2 to control the circuit to the motors 5 and 6.

The switch 10 is of usual construction 70 having a drum 11 mounted on shaft 12 and having contacts 13 and 14. A sheave wheel 15 is mounted on one end of the shaft 12 for rotating the drum 11.

A cable 16 is secured adjacent its one end 75 to the sheave 15, so that a short length is on one side of said sheave and a considerably longer length is on the other side of said sheave. The short length of the cable 16 extends within a casing 17 and is provided 80 with a counterweight 18 which normally pulls said sheave wheel 15 around, so as to close the limit switch 10 and when in this position the weight 18 rests upon the bottom 85 of the casing 17.

The long length of the cable 16 is trained from the sheave wheel 15 downwardly over a sheave 20, journaled in a bracket 20^a, on the bottom of the trolley 2, thence downwardly over a sheave 21 journaled in a bracket 22 90 which extends downwardly a considerable distance below the trolley to the one side of the path of travel of the load carrying device 7. A second bracket 23 of equal length to the bracket 22 extends downwardly 95 from the trolley 2 on the opposite side of the path of travel of the load device 7 and has a sheave 24 journaled therein. The cable 16 is trained from the sheave 21 across the path of travel of the load device 7 and 100 over the sheave 24 thence upwardly over a sheave 25 journaled in a bracket 26 on the bottom of the trolley 2, thence downwardly into a casing 27 around a pulley 28 secured to a counterweight 29, which is normally 105 supported on the bottom of the casing 27.

From the pulley 28 the cable is trained upwardly and over a sheave 30 journaled in the bracket 26 and then downwardly and is secured to the pulley 28. 110

- The counterweight 29 is considerably heavier than the counterweight 18, so that the pull of the counterweight 29 will be sufficient to overcome the counterweight 18 and the pull of the switch 10. Therefore, when the load device 7 engages and lifts the stretch of cable between the sheaves 21 and 24, the counterweight 18 will be lifted so as to cause the pull of the cable to be from the counterweight 18 to the counterweight 29, thus rotating the sheave wheel 15 and operating the switch 10 to break the forward or lifting circuit to the motors 5 and 6.
- 15 The load device or bucket 7 is provided with an arched fender or plate 31 on its upper surface adapted to engage the stretch of cable between sheaves 21 and 24.
- In Figure 6 I have shown a wiring diagram of the ordinary control circuits used for apparatus of this class and having my limit switch incorporated therein. In this diagram the letters A and B designate the positive and negative line wires, respectively, which connect through a line switch 32 with wires 33 and 34. When it is desired to raise the bucket 7 the controller 35 will be moved to bridge contacts 36 and 37, thus making a circuit from the positive wire 33 through the bridged controller contacts 37, through wire 37^a, through contacts 38 of the limit switch 10, through wire 39 to wire 40, then through the armatures of motors 5 and 6, to wire 41, and to wire 42 to the contacts 43 of the limit switch 10. From the contacts 43 the current flows through wire 44 to the bridged contacts 36 of the controller, to wire 34 and negative side of line through switch 32, thus completing the forward or raising circuit to the motors 5 and 6.
- When the load device or bucket 7 reaches the predetermined upper position the limit switch 10 will be automatically tripped or opened, thus breaking the circuit through the contacts 38 and 43 of the switch and opening both sides of the line carrying the forward or raising circuit to the motors 5 and 6.
- 45 50 After the switch 10 has been tripped and opened the controller 35 will be moved to bridge contacts 45 and 46 of the controller and unbridge the contacts 36 and 37 and a reverse circuit will then be made from the positive wire 33 to wire 47, through the bridged controller contacts 46 to wire 48, to wire 41 to the armatures of the motors 5 and 6, through the armatures of the motors to wire 40, to wire 49, to bridged controller contacts 45 to wire 50 and then to the negative wire 34 and negative side of line through line switch 32, thus reversing the motors 5 and 6 to lower the bucket.
- When the bucket or load device 7 reaches 65 the lower position shown in dotted lines and

indicated as position *a*, it is at its extreme safe height, and the fender 30 engages the cable 16 forcing it upward. The upward movement of the cable 16 will cause it to move from the weight 18 toward the weight 29 due to the greater weight of the weight 29. This will pull the sheave wheel 15 and trip or open the switch 10 when the load device has reached the point indicated as position *b*, thus breaking the forward or lifting circuit to the motors. After the circuit is broken the load device 7 will over travel, according to the speed at which it is traveling, the inertia of moving parts, and the braking applied until it reaches approximately the point indicated by position *c*, the counterweight 29 being lifted while the load device 7 is moving upwardly from position *b*, to position *c*.

After the switch 10 operates to open or break the forward or lifting circuit to the motors 5 and 6, this circuit cannot be again made until after the controller 35 has been thrown to the reverse, and the reverse circuit has been made to the motors to operate them in the reverse direction, which operation will lower the load device 7 and allow the switch 10 to automatically set itself again. However, the resetting of the switch 10 will not effect the operation of the motors 5 and 6, since when the controller 35 is reversed to make the reverse circuit to the motors the contacts 36 and 37 are unbridged and, therefore, the forward or lifting circuit is broken at the controller.

When the load device or bucket 7 is being lowered the counterweight 29 will be the first to be seated in its normal position. Then counterweight 18 will exert its power on the cable 16 and pull around sheave 15 so as to rotate the drum of the switch 10 and reset said switch.

It will be expressly understood that the usual crane hook may be substituted for the bucket 7, or other load devices may be used.

While I have shown and described one particular embodiment of my invention, I do not wish to be limited thereto since it is only illustrative and various changes in design, construction and combination of parts may be made without departing from the spirit of my invention as defined in the appended claims.

I claim:—

1. The combination with a hoisting crane trolley having a load carrying device, means for raising and lowering said device, and electric power means for operating said first named means, of a limit switch for breaking the forward operating circuit to said electric power means to control the upward movement of said load carrying device, and flexible means adapted to be tripped by said load carrying device for operating said switch, said last named means being adapted

- to permit an appreciable upward overrun of said load carry device after said means has been tripped.
2. The combination with a hoisting crane trolley having a bucket, means for raising and lowering said bucket, and electric power means for operating said first named means, of a rotary limit switch for breaking the forward operating circuit to said electric power means, a sheave wheel mounted on, and adapted to actuate said switch, a cable member secured to said sheave wheel and trained around other sheave wheels so as to extend across the path of travel of said bucket, said bucket being adapted to engage and trip said cable when it reaches a predetermined position thereby rotating said sheave wheel on said switch and breaking the circuit to said electric power means.
3. The combination with a hoisting crane trolley having a bucket, means for raising and lowering said bucket, and electric power means for operating said first named means, of a rotary limit switch for breaking the forward operating circuit to said electric power means, a sheave wheel mounted on, and adapted to actuate said switch, a cable member secured to said sheave wheel and trained around other sheave wheels so as to extend across the path of travel of said bucket, said bucket being adapted to engage and trip said cable when it reaches a predetermined position thereby rotating said sheave wheel on said switch and breaking the circuit to said electric power means, counterweights on said cable, and one of said counterweights being adapted to exert a pull on said cable to reset said switch when said bucket is lowered beyond its tripping position.
4. The combination with a hoisting crane trolley having a bucket, means for raising and lowering said bucket, and electric power means for operating said first named means, of a rotary limit switch for breaking the forward operating circuit to said electric power means, a sheave wheel mounted on and adapted to actuate said switch, a cable member secured adjacent its one end to said sheave wheel, the short end hanging from said sheave and the long end being trained around other sheave wheels so as to extend across the path of travel of said bucket, counterweights secured to the terminals of said cable, the counterweight on said short end of said cable being of considerably less weight than the counterweight on said long end, means for supporting said weights, said bucket being adapted to engage said cable and move it upwardly so as to first raise said light weight and rotate said sheave wheel on said switch, thereby actuating said switch to break the circuit to said electric power means and to then raise said heavy weight, and said weights being adapted to return said cable and switch to normal closed position when said bucket is lowered.
5. In a crane hoisting apparatus a crane trolley, a bucket mounted for vertical movement relative to said crane trolley, electrically operated means for raising and lowering said bucket, a rotary limit switch mounted on said trolley adapted to break the lifting circuit to said electrically operated means for raising and lowering the bucket, a sheave wheel mounted on and adapted to actuate said switch, an arched fender on said bucket, and means adapted to be tripped by said fender when said bucket is raised to a predetermined position for actuating said switch to break the lifting circuit to said electrically operated means, said last named means comprising a cable secured adjacent its one end to said sheave wheel, said cable having its short end hanging free from said sheave wheel and having a light counterweight secured thereto, sheaves supported on brackets extending below said trolley and spaced on each side of the path of travel of said bucket, the other end of said cable being trained over said last named sheaves so as to extend across the path of travel of said bucket, a counterweight of considerably greater weight than said first named counterweight secured to said long end of said cable, supports upon which said weights are adapted to rest when in their lower normal position, said fender on said bucket being adapted to engage and raise said cable when said bucket is raised beyond a predetermined position thereby rotating said sheave wheel on said switch and actuating said switch, and said counterweights being adapted to return said cable and switch to normal closed position when said bucket is lowered.
- In testimony whereof, I have hereunto signed my name.

SAM'L ARNOLD, 3d.
